UNITED STATES PATENT OFFICE.

OSCAR P. STRICKLER, OF YORK, PENNSYLVANIA, ASSIGNOR TO YORK FEED MACHINERY COMPANY, OF YORK, PENNSYLVANIA, A CORPORATION OF DELAWARE.

ROUGHAGE MILL.

Application filed June 24, 1922. Serial No. 570,637.

To all whom it may concern:

Be it known that I, OSCAR P. STRICKLER, a citizen of the United States, residing at York, in the county of York and State of Pennsylvania, have invented new and useful Improvements in Roughage Mills, of which the following is a specification.

This invention relates to roughage mills and has for its principal object the construction of a mill for cutting dry roughage particularly such as has the characteristics of dry corn fodder, or for grinding any kind of grain into a coarse or granulated meal.

Another object of the invention is the provision of a roughage mill so constructed to have an output capacity greater, for the size of mill, than that of the ordinary friction grinding mills.

Another object of the invention is to provide a roughage mill having rotating knives cooperating with relatively fixed cutters, the latter being however, yieldable to prevent jamming of the mechanism through non-uniform feeding of material between said knives and cutters.

A further object of the invention is the provision of a casing forming a receptacle in which is journalled a cutting drum provided with knives, the lower peripheral wall of the casing being constituted by a perforated screen having meshes of a size to deliver a product of the proper degree of fineness, and its upper side including a concave member having cutters co-operating with the rotating knives, said concave member being so arranged as to be capable of slight universal movement, and also bodily displaceable against a predetermined pressure to relieve the mill of the effects of overload when masses of excessive size are carried between the knives and cutters.

Still another object of the invention is the provision of emergency means for throwing open the concave member and simultaneously rendering the feeding mechanism inoperative.

A still further object of the invention is the provision of means providing for the equal and accurate adjustment of the knives so as to bring them within true cutting relation to the cutters.

Other objects will appear as the description proceeds.

The invention will first be hereinafter described in connection with the accompanying drawings, which constitute part of this specification, and then more specifically defined in the claims at the end of the description.

In the accompanying drawings, wherein similar reference characters are used to designate corresponding parts throughout the several views:—

Figure 1 is a side elevation partly in section of my improved roughage mill. 65

Figure 2 is a plan view of the same, parts thereof being broken away to show the interior of the casing.

Figure 3 is an end elevation taken partly in section. 70

Figure 4 is a side elevation of the reverse side of the mill from that shown in Figure 1, showing the operating mechanism.

Referring now in detail to the several figures the numeral 1 represents a casting 75 which is generally rectangular in shape at the base, and provided with flat sides as shown at 2 in Figure 3. The interior of the casting is hopper shaped, there being an opening 3 in the bottom thereof to provide 80 for the discharge of the ground roughage. The front and back portions of the casting extend upwardly as shown at 4 and 5 respectively, being provided with a re-entrant cut-out portion 6 having a circular curvature. 85 The edge of this cut-out portion is inwardly flanged as shown at 7 for a purpose hereinafter to be described. Heavy cast iron side plates 8 and 9 respectively are secured to the outer faces of the flat sides 2 of the casting 90 1 and extend upwardly therefrom following an irregular outline which is indicated in Figure 1 at the points designated by the numeral 10. Said cast iron sides are spaced apart and braced by means of the rigid bars 95 11, 12 and 13. Between the flanges 7 which extend inwardly from the opposite sides of the casting is a removable screen 14 which is made with a mesh of an appropriate size to permit the passage therethrough of roughage or grain meal ground to a desired fineness, and said screen is interchangeable with 100

screens of different mesh when the degree of fineness of the ground roughage is to be varied. The screen 14 is held in place against the lower faces of the flanges 7, by 5 means of tie rods 15, one for each flange, which lie beneath said flanges and are pivotally mounted to the casting by means of the pins 16 the latter being fixed to the casting and surrounded by a looped portion 17 of the 10 tie rods. The ends of the tie rods opposite the pivotal connection pass through a plate 18 which rests transversely upon the top edges of the upwardly extended portion 5 of the casting 1, each side of said plate being 15 provided with a projection 19 fitting in a recess in said casting. Nuts 20 threadedly engage the ends of said tie rods and are adapted to be tightened against the transverse plate 18. The screen 14 lies between 20 the flanges 7 and the tie rods 15 and when the latter are tightened the screen is firmly clamped into position. The plate 18 likewise is securely held in place by the tensioning of the tie rods through tightening of 25 said nuts. When it is desired, for any reason to remove the screen 14, the nuts 20 are loosened, the plate 18 raised so that the projections are unseated from the recesses, and the plate bodily moved over to the position 30 shown in dotted lines in Figure 1. The tension upon the tie rods having thus been loosened the screen 14 may be pulled out from between the flanges and tie rods and another screen substituted therefor.

35 The transverse plates 11, 12 and 13 and the screen 14 form a drum-chamber or receptacle in which is mounted the rotating element of the roughage mill. This comprises a knife-carrying drum 21 which includes a hollow casting having end headers 22 and a peripheral portion 23 joined thereto and having the peculiar shape shown in Figure 1. This peripheral portion comprises a series of knife seats with pockets adjacent 40 thereto, said knife seats comprising the angularly disposed flat faces 24 and 25, the former being bored and threaded as at 26 for the reception of the knife securing bolts 27. The knives 28 are elongated blades as 45 shown in Figure 3, beveled on their opposite longitudinal edges 29, Figure 1, and held in place between the flat shoulder 24 and a detachable plate 30 by means of the bolts 27. The ends of said knives project slightly beyond 50 the sides of the drum and are notched as shown at 31 in Figure 3, providing a tool engaging means for said knives, in the act of adjusting the latter when the bolts 27 are loosened. The double bevel 29 permits the 55 knives to be reversed presenting a new cutting edge when the old one has become worn.

60 The upper part of the drum-chamber between the plates 12 and 13 is open, and provided with a removable closure 32 which is concave in form and constructed in two

parts, an outer part 121, of cast iron and an inner part 122 of hardened steel bolted thereto by means of the bolts 123, the lower surface of which being curved in the form of a circle and having grinding points 33 constructed thereon, and cooperating with the edges of the knives 28. The grinding points have V-shaped apexes the points of which are presented in the direction in which the roughage is fed into the mill. The concave 75 member 32 is provided with extending ends 34 and 35 which overlap the plates 12 and 13 and are provided with set screws 36 which abut against the plates 12 and 13 and form means for adjusting the distance of the 80 grinding points 33 from the edges of the knives 28. Said set screws also function as limit stops to prevent the concave member 32 from moving inwardly into the path of 85 rotation of said knives.

On its outer back surface the concave member 32 is provided with spaced upstanding lugs 37 and 38 each provided with a slot 39 through which extend the angular ends 40 of the lever arms 41, Figure 2, the latter being secured to a shaft 42 journaled in bearings in the opposite sides of the sheet-metal members 8 and 9. The angular ends 40 are smaller in size than the slots 39 through which they extend so that the concave member 32 is capable of a limited up and down movement with respect to the angular ends 40, and also slight sidewise movement, both of said movements imparting to said concave member a slight universal 90 freedom of movement. This provision is made to prevent jamming of the mechanism should larger pieces of roughage than the machine is set to handle be introduced between the knives and grinding points. A 95 lever arm 44 is secured to the middle of the shaft 42 above the concave member 32, bearing against an upstanding lug 125. Said lever carries an adjustable weight 45. It will thus be understood that the concave member 32 is always maintained in closed position by a predetermined pressure equal to the weight 45 and variable by sliding said weight along the lever arm 44, and that it is capable 100 of slight rocking movement transversely about said lever as an axis to an extent permitted by the slots 39. The roughage is therefore ground between the knives and the grinding points under a uniform pressure determined by the mass and position of said 105 weight and when a quantity of roughage in excess of the capacity of the grinding elements is drawn between the latter the concave member rises against the pressure of said weight permitting the passage thereby 110 of said roughage.

In order to facilitate the adjustment of the knives 28 with respect to the grinding points the cast iron sides are provided with recesses 46 in Figure 1 on opposite sides of 115

the mill for the reception of a knife gauge. This knife gauge is not shown in the drawings but may be a simple straight edged member capable of seating accurately upon the bottoms of the recesses 46, and against which the edges of the knives 28 are aligned before tightening the bolts 27. In order to insert the gauge in the bottoms of said recesses, it is essential that the concave member 32 be turned back, this being done through means, hereinafter to be described.

The space between the plates 11 and 12 forms a feed opening for the roughage mill, adjacent which is arranged the feed chute 49 which is rectangular in form as shown in Figure 2, and is pivotally supported upon the rod 50, which extends transversely of said chute and is carried at the top of the vertical uprights 51 the latter being bent angularly at their ends as shown at 52 in Figure 2 and being secured to a stationary support. At its forward and back ends the chute is provided with shafts 53 and 54 on which are mounted the rollers 55 and 56 around which passes the belt conveyer 57. Uncut roughage is intended to be thrown upon this conveyer, with the ends of the stalks preferably presented longitudinally thereof and is carried thereby into the mill the feeding being assisted by the upper feed roller 58, shown in Figure 1, said upper feed roller and the conveyer being driven by positive means presently to be described. It will be observed that the belt conveyer is imperforate throughout the course traversed by the material to be cut on its way to the cutting drum there being no cracks or interstices, through which small particles may drop, making the conveyer adaptable for the feeding of small grains as for roughage.

In order to provide for uniform pressure upon the feed as it is drawn into the mill the chute 49 is constructed on its under side with a pair of extending lugs 59 through which passes a shaft 60, a bell crank lever 61 being journaled upon said shaft. The other end of the lever is pivotally mounted upon a shaft 62 carried by the extended end 4 of the casting 1. The other end 63 of said bell-crank lever is weighted as shown at 64 the chute 57 being pressed upwardly by said weight. By this means the rollers 55 and 58 are brought closer together or separated when variations occur in the thickness of the mass of the material being fed into the roughage mill. The bell-crank lever 61 is provided with a hand hold 65 so that should the feed be banked up in front of said rollers without passing therebetween said lever may be manually operated for depressing the chute and permitting the ingress of said material.

The mechanism for operating the roughage mill is best shown in Figures 3 and 4. The knife-carrying drum 21 is mounted

upon a shaft 66 which rests in lower half-bearings 67 and 68, the latter being secured to the side plates 8 and 9. The upper half-bearings 69 and 70 are secured to the lower half-bearings by means of bolts 71, but are not fastened to anything else. On the outer end of the shaft 66 the pulley 72 is mounted from which the power to operate the roughage mill is derived. A smaller spur gear 73 is keyed to the opposite end of the shaft 66, 75 which is constantly in mesh with the large gear wheel 74 the latter being splinably mounted upon a shaft 75. The shaft is slidably carried in bearings 76 and 77 said bearings being rigidly supported with respect 80 to a stationary part of the roughage mill. Loosely sleeved upon the shaft 75 on opposite sides of the gear wheel 74 are the hubs 80 and 81, bearing the sprocket wheels 78 and 79, said hubs being restrained from endwise movement on said shaft by being in abutment with the bearings 76 and 77 respectively. The hubs 80 and 81 are furnished with clutch depressions 85 capable of being engaged by the key 86, when the shaft 90 95 100 105 110 115 120 125 130 is slid in one direction or the other. The hub 84 of the gear wheel 74 has flat faces adjacent the clutch faces of the hubs and is held from substantial endwise movement by the proximity of said clutch faces to its flat faces.

The gear wheel 74 by being constantly in mesh with the gear 73 is always driven in the same direction and by being splinably mounted on said slideable shaft 75 it may be brought into engagement with either of the sprocket wheels 78 or 79 or be permitted to assume a neutral position out of engagement with either of said sprocket wheels. For operating the shaft 75 a hand lever 88 is provided pivotally mounted as at 89 upon a stationary support and carrying a perforated lug 90 which loosely surrounds a reduced portion 91 of said shaft so as to permit slight angular movement of said lever relative to said shaft. A collar 92 pinned to the end of said shaft holds said lever in place. By moving the lever 88 in one direction or the other a sliding movement is imparted to the shaft 75 and to the key 86 placing it into clutching engagement with the gear wheel 74 and with either of the sprocket wheels, or in neutral position.

The gears 93 and 94 are respectively secured to the outer ends of the shafts 53 and 95 upon which the feed rollers are mounted, said gears being movable in both directions for the purpose of reversing the direction of the feeding mechanism. These gears are respectively operated by the intermediate gears 96 and 97 which are mounted upon stub shafts 98 and 99 carrying sprocket wheels 100 and 101 respectively. The sprocket wheel 100 is connected with the sprocket wheel 78 by means of the chain 102

and the sprockets 79 and 101 are similarly connected by means of the chain 103. When the gear wheel 74 is in clutching engagement with the sprocket wheel 78 the latter is driven in a clockwise direction as viewed in Figure 4, driving the shaft 98 and the gear 96 which is attached thereto in a clockwise direction and imparting a counter-clockwise movement to the gear wheel 93. At the same time a gear wheel 104 which also is mounted upon the shaft 98 meshes with the gear 97 on the shaft 99, rotating the latter in a counter-clockwise movement to the gear wheel 94. This direction of movement to the gears 93 and 94, acts to feed the roughage into the mill. During this phase of movement of the operating mechanism the sprocket wheel 79 rotates freely on the shaft 75 in a counter-clockwise direction, being impelled by the chain 103.

When the lever 88 is thrown so that the gear wheel 74 clutchably engages the sprocket wheel 79 the sprocket wheel 101 is rotated in a clockwise direction by the chain 103. This imparts a direct counter-clockwise movement to the gear wheel 94 and an indirect clockwise movement to the gear 93 through the gears 96 and 104 which are mounted on the shaft 98. This reverses the direction of the feed, drawing the material away from the mill.

Notwithstanding the constructional expedients herein provided for preventing the jamming of the mill mechanism, it is inevitable that sometime something will be introduced between the knives and the grinding point, in the nature of foreign bodies such as tools, rocks etc. carelessly fed in with the roughage, which will interrupt the operation of the mill. For the quick elimination of such objects an emergency means is provided consisting of the hand lever 105, fixed to one end of the shaft 42 upon which are carried the lever arms 41 which support the concave member 32. When a stoppage of the machinery occurs this lever may be manually thrown toward the left, as viewed in Figure 1, instantly opening the concave member 32 which is capable of swinging to an extreme position shown in dotted lines at 106 in Figure 1. Simultaneously with the swinging open of the concave member the key 86 throws the gear wheel 74 into clutching engagement with the feed reversing mechanism by means of the bell-crank lever 107, having an arm 108 thereof engageable with the end of the shaft 75. Said bell-crank lever is pivotally connected at 109 to a bracket supported by the side of the roughage mill. The opposite end of the bell-crank is provided with a groove 111 in which is loosely seated an operating rod 112 the upper end of which makes pivotal connection as at 113 with a crank 114 on the end of the shaft 42. In order to prevent the open-

ing of the concave member 32 by normal operation of the lever 88 the upper end of the operating rod 112 is slotted as at 115 in Figure 4 providing a lost motion through which the operating rod may freely reciprocate when the lever 88 is moved.

The side plates 8 and 9 of the roughage mill are cut away as shown in Figure 2, forming sector shaped openings 116 extending from the upper edge of said side plates 75 to the lower half-bearings 67 and 68 in which the shaft 66 is mounted. The edges of the side plates adjacent these cutaway portions have secured thereto the flanged frames 117 and 118 as in Figure 2, the flanged portions 80 of said frames cooperating with the edges of the side plates to form channels in which are seated the edges of the sector shaped members 119 and 120. These members are removable for the purpose of permitting the withdrawal of the knife-carrying drum with its shaft from the drum chamber, and to render visible the clearance between the knives 28 and the grinding points, so that the set screws 36 may be manipulated to 90 adjust the concave member 32 to secure the proper clearance.

In the operation of this device, the roughage which, as hereinbefore stated, is in general of the character of dry corn fodder, is placed upon the conveyer belt 57 and drawn into the drum-chamber by means of the feed rollers 55 and 58 rotating in a forward direction. As it enters the drum-chamber the roughage is engaged by one of the knives 28 and cut into short lengths which fall into the concave pockets and are then thrown out by centrifugal force into contact with the grinding points on the under surface of the concave member 32. Here they are engaged by the knives which cooperate with the grinding points to cut the roughage into small particles. As the roughage is carried around in the pockets of the knife-carrying drum it is thrown against the screen 14 by 110 centrifugal force, and if fine enough to pass through the screen it is forced outwardly into the hopper formed by the casting 1 and finds its way by gravity into an appropriate receptacle placed beneath the grinding mill, 115 preferably upon the floor below. Moving of the weight 45 along the lever 44 regulates the pressure of the latter upon the concave member and controls the degree of fineness of the ground product. Material which is 120 not of sufficient fineness to pass through the screen is carried around in the pockets and again thrown against the grinding points to be acted upon a second time by the knives 28 and the process is carried on until all of 125 the roughage is properly ground.

Having described my invention what I claim as new and desire to secure by Letters Patent, is:—

1. A roughage mill comprising a recep- 130

tacle, grinding means in said receptacle and means for feeding material to said grinding means including a pair of cooperating rolls, one of said rolls being rotatable upon 5 a fixed axis, a conveyer carried by the other of said rolls, means for supporting said conveyer and said other roll, said supporting means being pivotally mounted at a point remote from said other roll, a lever engaging 10 said supporting means for releasing said conveyer from operative relation to the roll having the fixed axis, said lever being weighted for normally pressing said other roll toward the roll having the fixed axis, 15 and means for positively operating said rolls.

2. A roughage mill comprising a receptacle, rotatable cutting elements mounted in said receptacle, means forming a part of 20 the wall of said receptacle and provided with grinding points cooperably arranged with respect to said cutting elements, said means being mounted for slight universal movement with respect to said cutting elements.

3. A roughage mill comprising a receptacle, rotatable cutting elements mounted in said receptacle, means forming a part of the wall of said receptacle and provided 30 with grinding points cooperably arranged with respect to said cutting elements, said means being mounted for slight universal movement with respect to said cutting elements, and adjustable stops on said means to limit its inward movement toward said cutting elements.

4. A roughage mill comprising a receptacle, rotatable cutting elements mounted in said receptacle, means forming a part of 40 the wall of said receptacle, carrying grinding points cooperably arranged with respect to said cutting elements, lugs projecting exteriorly of said grinding point carrying means, said lugs being provided with perforations, means carried by said roughage mill and extending through said perforations, said means being sufficiently smaller than 45 said perforations to permit movement in all directions of said grinding point carrying means relative to said cutting elements.

5. A roughage mill comprising a receptacle, rotatable cutting elements mounted within said receptacle, means forming a part 55 of the wall of said receptacle and carrying grinding points, lugs extending exteriorly of said grinding point carrying means and provided with perforations, a shaft carried by said roughage mill, arms secured to said shaft having portions thereof extending 60 through said perforations, said extending portions being of sufficiently smaller dimensions than said perforations to permit slight movement in all directions of said grinding point carrying means, and means associated

with said shaft to impose a normal limit to 65 the opening movement of said grinding point carrying means.

6. A roughage mill comprising a receptacle, rotatable cutting elements mounted in 70 said receptacle, means forming a part of the wall of said receptacle and carrying grinding points, lugs projecting exteriorly from said grinding point carrying means, said lugs being provided with perforations, a shaft carried by said roughage mill, arms secured 75 to said shaft and having portions thereof extending through said perforations, said extending portions being of sufficiently smaller diamensions than said perforations to permit slight movement in all directions 80 of said grinding point carrying means, a weighted lever secured to said shaft for imposing a normal limit to the opening movement of said grinding point carrying means and manual means for rotating said shaft in 85 opposition to the weight of said lever for opening said grinding point carrying means.

7. A roughage mill comprising a receptacle, cutting elements rotatably mounted in 90 said receptacle, means forming a part of the wall of said receptacle and carrying grinding points, said grinding point carrying means being mounted so as to permit slight universal movement with respect to said cutting elements, a shaft mounted upon said roughage mill, arms carried by said shaft and associated with said grinding point carrying means to limit the universal movement thereof, means for pressing said grinding point carrying means toward closed 95 position by a predetermined pressure, manually operable means for opening said grinding point carrying means, a feed device for said roughage mill, means for operating said feed device and means actuated by said manually operable opening means for reversing the feed device operating means.

8. A roughage mill comprising a casting 100 forming a hopper, side walls secured to said casting and extending above it, a screen 110 mounted within said casting and forming with side walls a receptacle, a drum rotatably mounted within said receptacle, cutting elements carried by said drum, said drum being provided with pockets between 115 said cutting elements, a grinding point carrying element forming a part of the wall of said receptacle and provided with grinding points, a feed device for supplying roughage to said roughage mill, said drum functioning to throw said roughage into contact with grinding points by centrifugal force, to collect the ground roughage in said pockets and to throw it against said screen 120 by centrifugal force whereby the finely ground portions are expelled into said hopper and the insufficiently ground portions are returned to said grinding points.

9. A roughage mill comprising a receptacle, rotatable cutting elements mounted in said receptacle, means forming a part of the wall of said receptacle and provided with
5 grinding points cooperably arranged with respect to said cutting elements, said grinding points being detachably secured to said means, said means being mounted with slight

movement in all directions with respect to said cutting elements, adjustable stops on 10 said means to limit its inward movement toward said cutting elements.

In testimony whereof I have hereunto set my hand.

OSCAR P. STRICKLER.
